UNITED STATES PATENT OFFICE.

OSCAR A. SMITH, OF EAST CLEVELAND, OHIO, ASSIGNOR TO NATIONAL ACME COMPANY, OF CLEVELAND, OHIO, A CORPORATION OF OHIO.

FINGER BLOCK FOR WEDGE MECHANISM.

Application filed December 15, 1921. Serial No. 522,512.

To all whom it may concern:

Be it known that I, OSCAR A. SMITH, a citizen of the United States, residing at East Cleveland, in the county of Cuyahoga and State of Ohio, have invented certain new and useful Improvements in Finger Blocks for Wedge Mechanism, of which the following is a specification.

This invention relates to finger blocks or finger holding means for wedge mechanism on revolving spindles adapted preferably to operate in conjunction with automatically operative spring chucks or collets, an object of the invention being to provide improved mechanism of this general character particularly designed and adapted to be used in metal working machines wherein an improved means is provided for positively preventing or resisting the tendency of the operating fingers to spread through centrifugal force while the spindle is revolving during operation.

A further object of this invention is to provide an improved mechanism of this character which will be more simple and compact in structure, efficient and effective in operation, and economical to manufacture.

Other objects of this invention will appear in the following description thereof, reference being had to the accompanying drawings forming a part of this specification, wherein like reference characters indicate corresponding parts in the several views and wherein Fig. 1 is a side elevation partly broken away illustrating my invention; Fig. 2 is a right hand end view thereof; Fig. 3 is a section taken substantially on lines 3—3 of Fig. 1 in the direction of the arrow; Fig. 4 is a perspective view illustrating the finger block or holder and a finger pivot screw withdrawn therefrom; Fig. 5 is a detail view of a finger; and Fig. 6 is a detail view illustrating the various parts of the plunger mechanism.

Heretofore one of the main disadvantages residing in finger block mechanism was occasioned by the fact that upon shifting the wedge mechanism in order to release the fingers, and thereby permit the spring chucks or collets or the like to release themselves, the centrifugal force set up by the revolv-

ing spindle often caused the fingers to spread. This inadvertent or accidental spreading of the fingers interfered considerably with the efficiency or effective operation of the spring collet or chucking mechanism particularly, counteracting an effective opening or releasing of the collet or chuck. Thus the purpose of the present invention is to do away with these disadvantages and particularly eliminate such impediment to the opening or release of the chucking mechanism arising heretofore from centrifugal force.

Referring to the drawings it will be seen that the usual wedge or cone shaped sleeve 10 is slidably mounted upon the spindle 9 and is adapted to be shifted in any suitable manner upon the spindle relatively to the finger block. In the present instance the finger holding means or support comprises a finger block 12 adapted to be screwed onto the spindle 9 or otherwise secured thereto, and provided at the rear end thereof with a pair of diametrically opposed slots 13 and 14. Within each slot is pivotally mounted a finger or operating lever 15, pivoted by means of a pivot screw 17 inserted in suitable holes 16 tapped in the finger block at right angles to the slots 13 and 14, the pivots 17 adapted to pass through pivot holes 19 in the pair of fingers or operating levers. It will be noted that each finger 15 is provided at the rear end with a thrust portion 20 adapted to engage the rear end of the usual chucking tube (not shown) and to shift the same for the purpose of operating the chuck as is well known in the art. At the forward end 21 each finger is constructed to cooperate with the tapered portion 11 of the wedge.

In the rear or extended portion 18 of the finger holding means, a suitable distance away from the rearward face and at a suitable angle to the finger or lever slots 13 and 14, is bored a pair of two-section holes or slots 22 and 23, extending in the same plane and parallel to each other. These bores comprise portions or sections of enlarged diameter terminating in portions 24 and 25 of reduced diameter. In these holes or bores are housed a pair of plungers 26, the headed portions thereof corresponding substantially to the large diameter of holes 22 and 23, and

the stems thereof loosely fitting the small diameters 24 and 25 of the holes. In rear of and resting against the head of each pin 26 is housed in each hole a compression 5 spring 27, the same being held firmly in position by means of a pair of adjusting screws 28 cooperating with the threaded portions 29 of the respective holes or slots. By adjusting these screws 28 it will be readily seen 10 that the tenion of springs 27 may be adjusted or varied as desired, thereby varying the pressure exerted by the plungers upon the operating fingers or levers.

Into the rearward face and preferably at 15 a suitable distance above the pivoting holes 19 of the fingers, are milled stations or recesses 30. These recesses it will be noted form seats having the walls 31 thereof at right angles to the direction of operation of 20 the plungers 26, and the walls 32 thereof in substantial parallel relation thereto. As a result the milled stations or seats are angularly formed to correspond to the angular position of the plungers, and the plungers 25 25 project through the slots 13 and 14 into these stations or seats under constant pressure from the compression springs 27.

In operation it will be readily seen that 30 when the automatic spring collet or chuck releases as a result of the shifting of the wedge 10, so as to travel away from the finger block 12, the fingers 15 collapse as indicated in dotted lines in Fig. 1 by virtue of the outward lateral force exerted by the 35 plungers in rear of pivots 17 upon the operating fingers. The fingers however will be positively held in this position against the centrifugal force of the revolving spindle due to the fact that the spring controlled 40 plungers 26 exert continuous pressure upon the ends of the fingers thereby overcoming and counter-acting the centrifugal force. This resistance to the spreading of the fingers is increased due to the fact that the 45 fingers have a positive frictional engagement with the ends of the plungers. When the inner ends are forced inwardly the walls or faces 31 slide over the ends of the plungers, which frictional contact together 50 with the resistance of the springs forms a very effective and positive resistance to the spreading of the fingers.

It will be further seen that I have provided not only a mechanism for efficiently 55 controlling the position of the operating fingers but I have also provided a compact structure wherein the finger controlling mechanism is mounted entirely within the finger block thereby resulting not only in 60 more directness of operation but also in considerable simplification and economy in construction.

Although I have described my invention in its preferred form, it is to be understood 65 that I do not limit myself to the construc-

tion herein shown and described except in so far as defined in the claims and embraced within the scope thereof.

I claim as my invention:

1. The combination of a spindle, a finger 70 holder carried thereby, a chuck operating finger pivotally carried by said finger holder, means carried by the spindle for swinging said finger in one direction, and spring pressed means engaging the finger at the 75 rear of its pivotal point for swinging the finger in the opposite direction and operative in a direction transverse to the plane of movement of said finger.

2. The combination of a spindle, a finger 80 holder carried thereby, a chuck operating finger pivotally carried by said finger holder, means carried by the spindle for swinging said finger in one direction, and spring pressed plunger means for swinging the finger 85 in the opposite direction and operative in a direction transverse to the plane of movement of said finger.

3. The combination of supporting means, a plurality of chuck operating fingers pivotally carried thereby, means for engaging the opposed faces of said fingers for swinging the fingers in one direction to spread them, and means positioned to have a movement transversely to the plane of swing of 95 said fingers for frictionally and resiliently resisting such movement.

4. The combination of supporting means, a plurality of chuck operating fingers pivotally carried thereby, means for engaging 100 the opposed faces of said fingers for swinging the fingers in one direction to spread them, and means positioned to have a movement transversely to the plane of swing of 105 said fingers for frictionally and resiliently resisting such movement and comprising spring pressed plungers.

5. The combination of a spindle, a finger 110 block adapted to be connected thereto, chuck operating fingers pivotally carried by said finger block, and a pair of means coacting with said fingers for swinging the same, said means being operative in different directions and having the axis thereof extending outside the axis of the spindle and 115 in position to engage the finger at the rear of its pivotal point, thereby to exert a pushing action thereon.

6. The combination of a spindle, a finger 120 block adapted to be connected thereto, a chuck operating finger pivotally carried by said finger block, and means coacting with said finger for swinging the same, said means including a spring pressed plunger extending transversely to the spindle and 125 having the axis thereof extending outside the axis of the spindle.

7. The combination of a rotary spindle, finger holding means adapted to be connected thereto, a chuck operating finger pivoted 130

adjacent to one end thereof to said holding means, and means for swinging the finger and having one end engaging said finger in rear of its pivot and the other end extend through said finger holding means and terminating adjacent to the exterior thereof.

8. The combination of a spindle, a finger holder carried thereby and having a pair of opposed slots, chuck operating fingers pivoted in said slots, and a pair of means coacting with said fingers and operative in different directions and located to exert a pushing action on and thereby swing said fingers, each of said means having the axis thereof extending outside the axis of the spindle.

9. The combination of a finger holder having a pair of opposed slots, chuck operating fingers pivoted in said slots, and means for swinging said fingers, said means extending through the finger holder from the outside thereof into engagement with said fingers.

10. The combination of a spindle, finger supporting means mounted thereon, a chuck operating finger pivotally carried by said supporting means, and spring pressed means engaging the side of said finger for swinging the same.

11. The combination of a finger holder having a pair of opposed slots, chuck operating fingers in said slots, and adjustable spring controlled means for swinging said fingers, said means extending through the finger holder from the outside thereof into engagement with said fingers.

12. The combination of a rotary spindle, finger supporting means carried thereby, a chuck operating finger pivoted to said supporting means and swingable in the plane of the axis of said spindle, and an adjustable spring actuated plunger engaging the side face of said plunger for swinging the same.

13. The combination of a finger holder having a slot, a chuck operating finger pivoted in said slot and having a recess in its side and a spring controlled plunger carried by said holder and projecting into said recess.

14. The combination of a finger holder, a

chuck operating finger pivotally carried thereby and having at a side face thereof a plunger receiving seat and a plunger engaging said seat.

15. The combination of a finger holder, a chuck operating finger pivotally carried thereby and provided with a recess having angular walls, and a plunger projecting into said recess, said holder having a recess open at both ends for receiving said plunger.

16. The combination of a finger holder, a chuck operating finger pivoted thereto, and resilient means extending substantially through said holder for controlling the same.

17. A finger holder for chuck operating fingers having an axial slot and an angular hole communicating therewith and open at both ends.

18. The combination of supporting means, a plurality of fingers pivotally carried thereby, means for swinging said fingers in one direction, means for resisting such movement and comprising a plunger directly engaging each of said fingers at an angle to the sides thereof, and resilient means cooperating with said plunger.

19. The combination of supporting means, a plurality of pivoted fingers carried thereby, wedging means for engaging the opposed faces of the fingers at one end thereof thereby to spread said ends, and means for engaging the fingers at the opposite ends thereof and located at an angle to the sides of the fingers for spreading the opposite ends of said fingers.

20. The combination of a spindle, finger supporting means mounted thereon, a chuck operating finger pivotally supported intermediate its length on said supporting means, means for engaging the finger at one side of its pivotal point for operating the finger in one direction, and means for engaging the finger at the other side of its pivotal point and located at an angle to the side of the finger for operating the finger in the opposite direction.

Signed at Cleveland, Ohio, this 12th day of December, 1921.

OSCAR A. SMITH.
